COMBINED ELECTRIC ROASTER AND CABINET

Franz Wagner, Chicago, Ill., assignor to Nesco, Inc., Milwaukee, Wis., a corporation of New Jersey

Application March 4, 1953, Serial No. 23,872

Term of patent 14 years

(Cl. D81—10)

To all whom it may concern:

Be it known that I, Franz Wagner, a citizen of the United States, residing at Chicago, in the county of Cook and State of Illinois, have invented a new, original, and ornamental Design for a combined Electric Roaster and Cabinet, of which the following is a specification, reference being had to the accompanying drawing, forming part hereof, and wherein

Figure 1 is a top plan view of a combined electric roaster and cabinet embodying my new design;

Figure 2 is a side view; and

Figure 3 is a front view.

The side not shown in the drawing is substantially the same as the side shown in Figure 2.

I claim:

The ornamental design for a combined electric roaster and cabinet, as shown and described.

FRANZ WAGNER.
